UNITED STATES PATENT OFFICE.

MORDECAI M. NIXON, OF EDENTON, NORTH CAROLINA.

STREET-SWEEPER.

1,130,758.

Specification of Letters Patent.

Patented Mar. 9, 1915.

Application filed January 7, 1914. Serial No. 810,824.

To all whom it may concern:

Be it known that I, MORDECAI M. NIXON, a citizen of the United States, residing at Edenton, in the county of Chowan and State of North Carolina, have invented certain new and useful Improvements in Street-Sweepers, of which the following is a specification.

This invention relates to an improved street sweeper, and the principal object of the invention is to provide a sweeper having its brush-carrying trough adjustably mounted so that it may be raised out of engagement with the pavement, and provided with an adjustable flooring which may be moved closer to the brush bristles when desired.

Another object of the invention is to provide an improved operating means for the sweeping element which is automatically thrown into and out of an operative position when the trough is raised and lowered.

Another object of the invention is to provide an improved type of auxiliary brush which may be manually moved from an inoperative to an operative position.

Another object of the invention is to provide improved means for rotating the auxiliary brush, the rotating means for the brush being automatically moved into and out of an operative position when the brush is raised and lowered.

Another object of the invention is to provide the flooring board of the trough with improved fingers at its lower end which follow the unevenness of the pavement and are yieldably held in a normal position.

Another object of the invention is to provide an improved platform connecting the upper end of the flooring with the interior of a dirt-receiving chamber so that the flooring may be adjusted without space being left between the upper end of the flooring and the chamber.

Another object of the invention is to provide the chamber with an improved means for removing the dirt from the interior of the chamber.

This invention is illustrated in the accompanying drawings wherein—

Figure 1 is a side elevation of the improved street sweeper; Fig. 2 is a view similar to Fig. 1 looking from the opposite side of the street sweeper; Fig. 3 is a view similar to Fig. 1 with the brush-carrying trough moved to a lowered position; Fig. 4 is a vertical sectional view through the rear por-

tion of the street sweeper; Fig. 5 is a vertical sectional view through the brush carrying-trough looking in the opposite direction from the view shown in Fig. 4. Fig. 6 is a rear elevation of the brush carrying trough; Fig. 7 is a sectional view through the side wall of the brush-carrying trough taken along the line 7—7 of Fig. 5; Fig. 8 is a fragmentary sectional view of the longitudinally-extending shaft shown upon the brush-carrying trough in Fig. 1 and illustrating the means for permitting sliding movement of the shaft through the gears mounted on shaft; Fig. 9 is a sectional view taken along the line 9—9 of Fig. 2 with the auxiliary brush and its operating means shown in elevation; Fig. 10 is a fragmentary sectional view taken along the line 10—10 of Fig. 3 to show the means for operating the drop door of the dirt-holding chamber.

This street sweeper is of the automobile type in which there is provided a truck 15 which is supported at its forward end by the usual wheels 16, and is provided with the driver's cab 17 and engine hood 18. The dirt receptacle, or chamber, 19 is carried by the truck behind the driver's cab and is provided with a drop door 20. This drop door is hinged at one end, as shown at 21, and is provided with suspending chains 22 which are wound upon a shaft 23 extending through the receptacle. A ratchet wheel 24 and removable handle 25 are mounted upon the outer end of the shaft 23 at one side of the receptacle and the pawl 26 is pivotally secured to the side wall of the receptacle and engages the ratchet wheel so that the drop door may be held in a raised position. It will thus be seen that by releasing the pawl with the lever 26', the drop door may be permitted to drop to the dotted-line position shown in Fig. 3 and the machine then backed to cause the dirt in the receptacle to be deposited upon the ground. The handle can then be attached and turned to raise the door and the pawl will then prevent the shaft from rotating to permit the door to drop. A door 19' is provided for ascertaining whether the receptacle is full.

The rear portion of the truck is supported by the wheels 27 and 28 which are rotatably mounted by the axle 29 supported in the journals 30. The wheel 27 is provided with external gear teeth 31, and the wheel 28 is provided with internal gear teeth 32, the gear teeth of the wheels 27 and 28 providing

means for transmitting motion to the various shafts which are to be hereinafter described. The side walls 33 and 34 of the receptacle extend beyond the inclined rear wall 35 of the receptacle, as shown in Fig. 4, the wall 34 being provided with an upwardly-extending arcuate slot 36, and the wall 33 being provided with a smaller slot 37 positioned to communicate with the gear teeth 31 of the supporting wheel 27.

The auxiliary brush, together with its operating mechanism, is mounted between the side walls 33 and 34 to the rear of the supporting wheels 27 and 28, and is caused to rotate by having its operating means brought into engagement with the teeth 32. This auxiliary brush 38 is mounted upon a shaft 39 which is rotatably supported by the arm 40 leading from the sleeve 41 slidably mounted upon the supporting shaft 42. The shaft 42 is carried by the side bars 43 of the truck and is provided with a groove 44 in which a key 45 extends to prevent the sleeve from rotating upon the shaft 42. This shaft 42 is rotatably mounted, and it will thus be seen that when desired, the sleeve may be rotated by turning the shaft 42. A short shaft 46 is rotatably supported by the bracket arms 47 which are carried by the guiding arm 54 and is provided with bevel gears 48 and 49. The gear 49 meshes with the bevel teeth 50 of the crown gear 51, which crown gear is rotatably mounted upon the outer-end portion of the sleeve 41. A rod 52 is carried by the side walls and is bent intermediate its length to form the downwardly-extending curved guide-way 53 which extends behind the shaft 42, as shown in Fig. 4. An arm 54 is carried by the brush shaft 39 and extends into the guide-way 53 so that when the shaft 42 is rotated, the guiding arm 54 will cause the sleeve to move longitudinally upon the shaft to the dotted-line position, as shown in Fig. 9. The spring 55 yieldably holds the brush 38 pressed against the side of the curb so that it will get all the dirt, the rollers 38' preventing the brush from catching in cracks or uneven places. A lever 57 is connected with one end of the shaft 42 and is connected with the latch lever 58 by means of the rod 59. This latch lever 58 is mounted upon the side of the driver's cab so that the driver can operate the latch lever to swing the auxiliary brush from an inoperative position to an operative position, and then return the brush to the inoperative position when desired without leaving the cab. This auxiliary brush would be used for sweeping in gutters where the main brush does not travel, and would also be used for collecting dirt which the driver does not think will be taken up by the main brush.

The brush-carrying trough which is slidably connected with the side walls 33 and 34

is provided with the side walls 60 and the adjustable bottom 61. The side walls are provided with longitudinally-extending tongues 62 which fit into grooves 63 formed in the side walls 33 and 34 to guide the sliding movement of the trough. The rack bars 64 which are carried by the side walls 60 of the trough are engaged by the gears 65 mounted upon the shaft 66, and it will thus be seen that when the shaft 66 is rotated, the trough will be longitudinally adjusted. A gear 67 mounted upon the outer end of the shaft 66 meshes with a worm gear 68 carried by the shaft 69, which shaft 69 is provided at its forward end with a bevel gear 70 meshing with the bevel gear 71 of a ratchet wheel 72. This ratchet wheel 72 is engaged by the pawl 73 and is provided with a handle 74 so that the driver can rotate the shaft 69 to adjust the position of the trough.

The trough bottom 61 is slidably mounted upon crank shafts 75 by means of the elongated eyes 76, and is connected with the upper-end portion of the rear wall of the receptacle 19 by means of the plates 77 which are pivotally connected together, as shown in Fig. 4 so that the plates 77 may move when the trough is longitudinally adjusted and not interfere with the bottom 61. It will also be seen that this permits the bottom to be adjusted longitudinally independent of the trough. The crank shafts extend through the side wall at one side of the trough and are bent to form fingers 78 which engage the latches 79 so that the crank shafts may be held in an adjusted position, and the bottom 61 adjusted with respect to the apron 80, which carries the brushes 81. It will thus be seen that as the bristles of the brush wear off, the bottom of the trough may be brought nearer to the apron to compensate for this wear.

A threaded stem 82 has its upper end extending into an internally-threaded sleeve 83 carried by the bottom 61 and has its lower end provided with a bevel gear 84 which meshes with a bevel gear 85 mounted upon a transversely-extending shaft 86. This shaft 86 is rotatably mounted in the side walls 60 of the trough and is provided at one end with a removable handle 87, by means of which the shaft 86 may be rotated. By rotating this shaft 86, the stem 82 may be rotated to move the bottom 61 longitudinally between the side walls 60.

Fingers 88 are connected with the lower end of the trough bottom 61 by means of hinges 89 and are connected with the yoke 90 by means of the links 91 by having their inner ends formed into eyes 92 through which the yoke 90 passes. Springs 93 are carried by the links and yieldably hold the fingers 88 in engagement with the pavement

- and tend to cause the fingers to conform to the surface of the pavement over which they travel and thus prevent dirt from being left in the uneven places in the pavement.
- 5 These fingers 88 extend beneath the lower flight of the brush-carrying apron, as shown in Fig. 5, and have their lower edges tapered as shown so that the brushes will easily sweep the dirt onto the fingers and then 10 convey the dirt up the trough bottom 61. When the brushes reach the top of the trough bottom, the dirt is thrown in the mouth of the receptacle and falls into the bottom of the receptacle. A guard plate 15 94 is provided to prevent any danger of the dirt being thrown past the receptacle mouth. This guard plate is pivotally mounted so that it will not interfere with the longitudinal movement of the trough.
- 20 The apron 80 passes around rollers 95 and 96 which are mounted upon shafts 97 and 98. The rollers 96 are idler rollers and the roller 95 which is rigidly mounted upon shaft 97 is the drive roller which gives 25 movement to the apron. This drive shaft is provided with suitable tighteners 99 of the ordinary type used for tightening a belt. A longitudinally-extending shaft 100 is rotatably mounted by the bearings 101 and 30 carries a bevel gear 102 which meshes with a bevel gear 103 mounted upon the roller-supporting shaft 97. This shaft 100 is provided with a longitudinally extending groove 104 to receive the key 105 of the bevel 35 gear 106. The bevel gear 106 rotates with the shaft 100 but permits the shaft to move longitudinally through the bevel gear when the trough is longitudinally adjusted. A journal bracket 107 is carried by the side 40 wall 33 of the receptacle 19 and is provided at its outer end with a bearing 108 through which the shaft 100 passes. An abutment 109 is carried by the journal bracket and engages the lower end of the bevel gear 106 45 to prevent the bevel gear from moving out of the desired position. A transmission shaft 110 is carried by the journal bracket and is provided at its upper end with a bevel gear 111 which meshes with the bevel 50 gear 106 and causes the shaft 100 to rotate when its clutch 112 is in engagement with the clutch 113 of the gear wheel 114. This gear wheel 114 is rotatably mounted by means of the journal 115 and extends 55 through the slot 37 and engages the gear teeth 31 of the wheel 27 so that the gear wheel 114 will rotate continually when the machine is in motion. The clutch 112 is carried by a pivotally mounted bell-crank 60 lever 116 which is yieldably held in a normal position by the spring 118 and yieldably connected with the rocker arm 119 by means of the spring 120. The springs 118 and 120 normally hold the bell-crank lever 65 in the position shown in Fig. 1 so that
- when the brush trough is in the raised position, the clutch 112 will be held out of engagement with the clutch 113, and the transmission shaft 110 thus prevented from rotating. The lower end of the shaft 110 is 70 rotatably supported by the clutch 112, but is not rigidly connected with the clutch, and therefore the shaft will not rotate unless the clutch 112 is in engagement with the clutch 113. A rib 121 is carried by the 75 trough and is positioned to engage the rocker arm 119 and to bring the clutch 112 into engagement with the clutch 113 when the trough is moved to the lowered position shown in Fig. 3. Pins 122 are carried by 80 the side walls of the trough and are engaged by catches 123 carried by the side walls of the receptacle 19 to limit the downward movement of the trough.
- The operation of this machine is as follows: When the machine is being moved from one place to another and it is not desired to have the brush operate, the trough is raised to the position shown in Figs. 1 and 2 by rotating the shaft 69 as already 85 described, and the clutch 112 will then be out of engagement with the clutch 113 so that the brush-operating mechanism will not operate. When it is desired to use the machine, the trough is lowered and this will 90 bring the clutches into engagement and cause the apron to travel through the trough to sweep the dirt upon the pavement up the trough and deposit the same in the receptacle. If it is desired to remove the 95 dirt from a gutter, the latch lever 58 is moved by the driver to lower the auxiliary brush and this brush will then be moved to the dotted-line position shown in Fig. 9 so that the dirt in the gutter will be swept 100 out of the gutter and guided beneath the machine beneath the receptacle so that it 105 will be taken up by the main brush.
- As soon as the receptacle is filled, the drop door 20 may be lowered and the machine 110 then moved rearwardly a short distance to cause the dirt to pass out through the bottom of the receptacle and be deposited in a pile beneath the trough truck. The drop door can then be raised and held in the 115 closed position, and the machine is then again ready for use.
- When the brush has become worn a sufficient amount so that it does not closely engage the trough, the crank shaft 75 can be 120 adjusted to move the trough bottom closer to the brush apron, and this will accommodate for the wear upon the brushes. The trough bottom can also be adjusted longitudinally of the mechanism described to 125 compensate for the wear upon the fingers 88.
- A street sweeper has thus been provided which is very efficient in operation and which is so constructed that the operating means for the brush will be normally held 130

in an inoperative position when the trough is raised and which will be automatically thrown into operation when the trough is lowered for use. A machine has also been provided in which there is provided an auxiliary brush for removing dirt from a gutter and guiding the dirt to a position where it can be taken up by the main brush. The operating means for this auxiliary brush is so constructed that it will not operate when the brush is in a raised position, but will be automatically moved into an operative position when the auxiliary brush is lowered. This machine will therefore thoroughly clean all parts of a street and make it unnecessary to have sweepers follow the machine to remove the dirt from the gutter or to take up dirt which has been swept into the gutter by the sweeping machine.

20. What is claimed is:

1. A street sweeper comprising a receptacle, a trough connected with said receptacle for vertical adjustment, an endless cleaner passing through said trough, a driving shaft carried by said trough for rotating said endless cleaner, a gear slidably mounted upon said shaft, a bracket carried by said receptacle and engaging said gear, a driven shaft carried by said bracket and provided 25 with a gear meshing with said first-mentioned gear, a rotary clutch, a clutch collar carried by said driven shaft, pivotally mounted operating means for said clutch collar carried by said receptacle, resilient means 30 yieldably holding said pivotally mounted means in its normal position to normally hold said clutch collar and rotary clutch out of engagement, actuating means for said operating means, resilient means 35 connecting said actuating means and operating means, and means carried by said trough for engaging said actuating means when said trough is moved to a lowered position to bring said clutch collar and rotary clutch 40 into engagement.
2. A street sweeper comprising a receptacle, a trough connected with said receptacle for vertical adjustment, an endless cleaner passing through said trough, a driving shaft carried by said trough for rotating said endless cleaner, a gear slidably mounted upon said shaft, a bracket carried by said receptacle and engaging said gear, a driven shaft carried by said bracket and 45 provided with a gear meshing with said first-mentioned gear, a rotary clutch, a clutch collar carried by said driven shaft, a bell-crank lever having one end engaging said clutch collar, resilient means yieldably 50 holding said bell-crank lever in a normal position, a rocker shaft having an arm, resilient means connecting said rocker shaft arm with said bell-crank lever, and means carried by said trough for engaging said rocker shaft arm and moving said clutch collar 55

into engagement with said rotary clutch when said trough is moved to a lowered position.

3. A street sweeper comprising a receptacle, a trough carried by said receptacle, 70 said trough comprising side walls, a flooring, means for longitudinally adjusting said flooring, a guide-way connecting the upper portion of said flooring with the interior of said receptacle, sweeping means traveling through said trough and engaging said flooring, and operating means for said sweeping means.

4. A street sweeper comprising a receptacle, a trough carried by said receptacle, 80 means for vertically adjusting the position of said trough, a flooring for said trough, means for longitudinally adjusting said flooring, cleaning means in said trough, and operating means for said cleaning means. 85

5. A street sweeper comprising a receptacle, a trough carried by said receptacle, a flooring for said trough, eyes carried by said flooring, crank shafts carried by the side walls of said trough and passing 90 through said eyes, a cleaner positioned in said trough, movement of said crank shafts adjusting said flooring with respect to said cleaner, guiding fingers carried by said flooring means for longitudinally adjusting 95 the position of said flooring in said trough, and means for operating said cleaner.

6. A street sweeper comprising a receptacle, a trough slidably connected with said receptacle, rack bars carried by the side 100 walls of said trough, means engaging said rack bars for vertically adjusting said trough, a flooring slidably mounted between the side walls of said trough, an internally threaded sleeve carried by said flooring, a stem having one end threaded and extending into said sleeve, means carried by the side walls of said trough for rotating said stem, a guide way connecting the upper-end portion of said flooring with the interior of 105 said receptacle, sweeping means in said trough, and means for operating said sweeping means.

7. In a street sweeper a receptacle, rotatably-mounted supporting wheels for said receptacle, annular rack teeth carried by one of said wheels, a supporting shaft carried by said receptacle, a sleeve slidably mounted upon said shaft, a crown gear provided with a shoulder constituting a bevel gear rotatably carried by said sleeve, an arm extending from said sleeve, a journal bracket extending from said sleeve, a guide-way extending between said arm and bracket and extending from a point above said shaft and curved downwardly toward one side of said receptacle, a brush-carrying shaft extending from said arm, a bevel gear carried by said brush shaft, a guiding finger extending from said brush shaft into said 110 115 120 125 130

- guideway, a spring placed upon said brush shaft between said arm and finger, a transmission shaft rotatably carried by said bracket and provided with a bevel gear 5 engaging the bevel gear of said crown gear and provided at its opposite end with a bevel gear for engaging the bevel gear of said brush shaft, and means for rotating said first-mentioned shaft for bringing said 10 crown gear into engagement with the gears of said supporting wheel and the bevel gear of said brush shaft into engagement with the adjacent bevel gear of said transmission shaft.
- 15 8. A street sweeper comprising a receptacle, a main brush for said receptacle, means for operating said main brush, supporting wheels for said receptacle, an an-
- nular gear carried by one of said wheels, a rotatably-mounted auxiliary-brush operating means carried by said receptacle adjacent said last mentioned wheel, and means for automatically bringing said brush-operating means into engagement with said gear when said auxiliary brush-operating 20 means is lowered and for automatically moving said operating means out of engagement with said gear when said auxiliary brush-operating means is raised.
- In testimony whereof I affix my signature 25 in presence of two witnesses.
